UNITED STATES PATENT OFFICE.

CHARLES A. DRYER, OF CHAMPAIGN, ILLINOIS.

EJECTOR.

No. 812,026.

Specification of Letters Patent.

Patented Feb. 6, 1906.

Application filed May 23, 1905. Serial No. 261,734.

To all whom it may concern:

Be it known that I, CHARLES A. DRYER, a citizen of the United States, and a resident of Champaign, in the county of Champaign and State of Illinois, have invented a new and Improved Ejector-Pump, of which the following is a full, clear, and exact description.

This invention relates to improvements in pumps especially designed for driven tubular wells, the object being to provide a very simple and novel form of head for receiving and discharging fluid under pressure into the well-tube to elevate the water therein.

I will describe an ejector-pump embodying my invention and then point out the novel features in the appended claim.

Reference is to be had to the accompanying drawings, forming a part of this specification, in which similar characters of reference 20 indicate corresponding parts in both the figures.

Figure 1 is a sectional elevation of a pump embodying my invention, and Fig. 2 is a section on the lines *xx* of Fig. 1.

Referring to the drawings, 1 designates the well-tube, which is driven in the ground in the usual manner, and extended downward in the well-tube is a liquid-pressure tube 2, which is closed at the lower end by a cap 3. Mounted on the lower portion of the tube 2 is a head comprising two cup-shaped members 4 5. As here shown, these members 4 5 are conoidal and arranged in reverse directions—that is, with their larger ends adjacent to each other. These ends are spaced apart to form an annular port 6. It is designed that this port 6 may be regulated as to width, and therefore the members 4 and 5 are adjustable toward and from each other on the tube 2. It will be noted that the facing walls of the members 4 and 5 are inclined upward and outward, so that the fluid-pressure acts in an upward direction.

As a means for causing the adjustment the 45 member 4 has an interiorly-threaded ex-

tension 7 for engaging an exterior thread 8 on the tube 2, and this thread 8 is also engaged by a jam-nut 9. The member 5 has an interiorly-threaded downwardly-extended frame portion 10 engaging an exterior thread 50 11 on the tube 2, and this extended portion 10 is engaged by a jam-nut 12. The cup-shaped or conoidal members form a comparatively large air-chamber 13, which receives air from the tube 2 through a plurality of 55 ports 14, formed in said tube within the chamber.

In the operation the fluid under pressure is passed down through the tube 2 and enters the chamber 13, from which it discharges in 60 the well-tube through the annular port 6, thus creating an upward suction in the pipe, which serves to raise the liquid in the well-tube.

Having thus described my invention, I 65 claim as new and desire to secure by Letters Patent—

The combination with a well-tube of a fluid-pressure tube extending into the well-tube and having a plurality of perforations near 70 the lower end, a cap having screw-threaded engagement with the lower end of the pressure-tube for closing the same, a head comprising cup-shaped members having screw-threaded engagement with said pressure-tube, the adjacent open ends of said members 75 being spaced apart to form an annular port, the walls thereof being inclined upward and outward, the said port being centrally arranged with respect to the perforation and 80 jam-nuts for locking the said members as adjusted.

In testimony whereof I have signed my name to this specification in the presence of two subscribing witnesses.

CHARLES A. DRYER.
